(57) CLAIM

The ornamental design for a garden kneeler, as shown and described.

DESCRIPTION

FIG. 1 is a front-top-right side perspective view of the garden kneeler showing my new design;

FIG. 2 is a rear-bottom and left side perspective view thereof;

FIG. 3 is a front elevational view, the rear elevational view being a mirror image thereof;

FIG. 4 is a left side elevational view, the right-side elevational view being a mirror image thereof;

FIG. 5 is a top plan view thereof;

FIG. 6 is a bottom plan view thereof; and,

FIG. 7 is an exploded front-top and right-side perspective view thereof.

The broken lines indicate unclaimed portions of the garden kneeler and form no part of the claimed design.

1 Claim, 7 Drawing Sheets
